UNITED STATES PATENT OFFICE.

JOSEPH E. FORSYTH, OF CHICAGO, ILLINOIS, ASSIGNOR OF ONE-FOURTH TO
THOMAS L. PARKER, OF CHICAGO, ILLINOIS.

TRAIN-PIPE COUPLING.

SPECIFICATION forming part of Letters Patent No. 693,125, dated February 11, 1902.

Application filed November 12, 1900. Serial No. 36,291. (No model.)

To all whom it may concern:

Be it known that I, JOSEPH E. FORSYTH, a citizen of the United States, residing at Chicago, in the county of Cook and State of Illinois, have invented a new and useful Improvement in Train-Pipe Couplings, of which the following is a specification.

My invention relates particularly to automatic train-pipe couplings for passenger trains, though not limited to use on such trains.

My primary object is to provide an exceedingly simple construction of this nature well adapted for use in effecting the simultaneous coupling of the air-brake, signal, and steam pipes when two cars or an engine and car are coupled together. In the construction shown no automatic valve is employed; but it is intended that any suitable means shall be employed for operating the valve without the necessity of going between the cars.

In the accompanying drawings, which illustrate my invention in its preferred form, Figure 1 represents portions of two cars and their couplings and shows the train-pipes equipped with the improved train-pipe coupling; Fig. 2, a plan view of the train-pipes, certain parts being removed; Fig. 3, a sectional view illustrating the manner in which each train-pipe coupling member is supported; Fig. 4, a longitudinal vertical section through two companion coupling members; Fig. 5, a view in side elevation of a coupling member, and Fig. 6 a view in end elevation of the same.

A A' represent portions of the substructure of two cars; B B', suitable draw-bars connecting the cars; C C', companion train-pipe coupling members; D D', signal-pipes of the two cars; E E', air-brake pipes of the two cars; F F', hose or other suitable connections for the steam-pipes of the two cars, only one of which (designated F²) is shown.

The train-pipes of each car are supported from the bottom of the car by hangers a at some distance from the end of the car and have suitable connections at their extremities with the integrally-formed coupling-head provided therefor. As clearly appears from Figs. 4 and 5, each coupling-head has a central perforated brake-pipe head b, curved for-

wardly-projecting inclined guide arms or horns b' b² supported from said head b, a signal-pipe head c directly above the head b, and a steam-pipe head d directly below the head b. Each of the heads b and c is provided at its front or outer face with an annular recess receiving a rubber gasket e. The gasket e is provided with an annular flange e', by means of which the gasket is retained, and in the rear of the gasket is an annular recess e², which permits the air-pressure to get behind the gasket and force the latter forward. Each head d is provided with annular recesses f' f², the latter receiving an annular diaphragm f³, secured in place by an annular threaded ring f⁴. The diaphragm f³ receives at its central perforation a ring f⁵, having a flange f⁶. A ring f⁷ is rigidly fixed to the projecting portion of the ring f⁵, and the inner margin of the annular diaphragm is firmly secured between the ring f⁷ and the flange f⁶. The flange f⁶ receives an annular packing-ring f⁸, which is preferably of comparatively hard material of suitable composition which swells after the steam is admitted. The ring f⁷ is capable of backward or forward movement in the annular recess f', thereby permitting the packing-ring f⁸ to yield under pressure. Steam may enter the recess f' in the rear of the diaphragm and help to effect a perfect joint. At the rear of the head d is an annular hose connection g, and at the rear of the head b is a pipe-attaching annular boss h. The rear of the head c is internally threaded to receive the pipe which connects therewith.

To permit longitudinal movement of the train-pipe coupling-heads, I prefer to provide the pipes D D' with a bend or loop k and to insert a spring k' at the neck of said loop, suitable spring-retainers k² being provided for receiving said spring; also, to provide the pipes E E' with loops l, the necks whereof are provided with spring-retainers l', which receive springs (not shown) similar to the springs k'.

The preferred manner of supporting the coupling-heads is illustrated in Fig. 3, where-in is shown a clip or bar m, secured to the under surface of the draw-bar head, and a collar m', which receives the boss h of a coup-

ling member and is supported by inclined coil-springs m^3 , attached to lugs m^3 on said collar and to the extremities of the bar m .

For emergency the train-pipes are provided 5 with branch pipes n n' , having the usual hand-couplings for connection with cars not equipped with the improved coupling device. Three-way cocks n^2 are provided for the train-pipes, and by means of these cocks both 10 passages from either end of each train-pipe may be closed or the train-pipes may be connected through the improved coupling-heads or through the old form of hand-coupling, as desired.

15 The head b has diagonally opposite curved surfaces p , and the arms or horns b' b^3 are provided at their bases with inner concave surfaces p' , which serve to receive the convex surfaces p of the companion coupling 20 member. The convex surfaces p end at abrupt shoulders p^2 , flanking the bases of the prongs b' b^3 , said shoulders affording between them recesses for receiving the bases of the horns of the companion coupling member. 25 The space between each set of shoulders p^2 corresponds with the width of the horn at its base, so that when two coupling members are brought together there is such an interlocking of parts as to prevent any relative rotary 30 movement between coupling members. In addition the concavities at the bases of the horns of each coupling member fit snugly over the convexities of the companion member, thereby preventing any movement except a direct end-to-end movement of separation.

It will be understood that the coupling-heads are so disposed that the horns of each coupling-head have the same position with 40 relation to the end of the car whereat they are located—that is, if the horn b' of a coupling member at one end of a car viewed by a person standing in front of the car projects upwardly and to the right the corresponding 45 horn of the coupling member at the other end of the car will have the same relative position when viewed from a corresponding position at the opposite end of the car. When any two ends of any two cars come together, 50 therefore, the horns of companion coupling members are properly located to guide the members together and cause them to interlock. The gaskets project far enough beyond the flat surrounding faces of the pipe-heads 55 to cause companion gaskets to be firmly pressed together when the cars are coupled, the coupling-heads being somewhat retracted at such time against the action of their springs. It will be understood that the loops 60 in the metallic pipes cause the pipes to act as springs, permitting retraction of the coupling members, and in the restoring movement the coil-springs at the necks of the loops act with the resilience of the pipes to 65 force the coupling members outwardly.

By employing coupling-heads of the kind described, each equipped with two diagonally

opposite horns located and spaced as herein described, the coupling-heads may be considerably out of alignment as the cars approach each other and still be properly guided together. This is of particular advantage in effecting a coupling where the cars are at a sharp curve of the track. After the coupling-heads have been properly guided together and have become firmly interlocked practically all yielding takes place in the pipes and their supports. After a coupling has been effected the valves n^2 may be turned to place the train-pipes in communication through the coupling-heads. Prior to uncoupling the cars the valves n^2 are turned to produce dead ends for their respective pipes. If desired, the train-pipes may be connected through the branch pipes n n' , which are equipped with the usual hand-couplings. The valve n^2 may then be turned to admit pressure through said branch pipes, the valves at this time serving to close the passages through the coupling-heads of the automatic device. It may be further remarked that one of the shoulders p^2 flanking each horn-base lies in substantially a vertical plane, and since the spaces between the horn-bases correspond to the widths of the horn-bases the remaining shoulder of each horn-base lies in substantially a horizontal plane. Otherwise stated, one of the junctions of each horn-base with the convex surfaces p lies in a vertical and the other in a horizontal plane. Thus each space is symmetrical with relation to a horn-base.

The loops k and l are preferably separately formed and of tempered steel, being inserted in the course of the train-pipes in the manner shown.

The construction described is for the purpose intended one of great simplicity, and in operation the coupling members have a direct end-to-end pressure when the companion gaskets come into contact with each other, thereby avoiding danger of the gaskets becoming dislodged or injured. All of the gaskets lie in a transverse plane and are supplied with fluid-pressure for increasing the efficiency of the joint.

Changes in minor details of construction within the spirit of my invention may be made by those skilled in the art. Hence no limitation is intended by the foregoing detailed description, except as shall appear from the appended claims.

What I claim as new, and desire to secure by Letters Patent, is—

1. In a train-pipe coupling, an integrally-formed movable coupling-head having steam and air passages whose orifices lie in the same vertical plane, a soft yielding air-expanded gasket at the air-passage orifice, and having a transverse outer bearing-surface, and a yielding steam-actuated diaphragm at the steam-passage orifice, equipped with a comparatively hard packing-ring having a transverse outer bearing-surface, said gaskets being adapted to form a tight joint with corre-

sponding gaskets of a companion coupling-head under longitudinal pressure between coupling-heads, substantially as described.

2. In a train-pipe coupling, the combination 5 of a yieldingly-held coupling-head, comprising a central perforated pipe-head, forwardly-projecting inclined guide-arms supported therefrom, and two additional pipe-heads, one supported above and the other below said first-named pipe-head, soft yielding gaskets for said central head and one of the other heads, annular air-passages e^2 being provided in the rear of said gaskets, a relatively hard gasket for the remaining pipe-head, and 15 a fluid-held diaphragm supporting said last-named gasket, substantially as described.

3. In a train-pipe coupling, a coupling-head having annular recesses, an annular diaphragm secured at a shoulder of one of said 20 recesses, an annular ring secured to the inner margin of said annular diaphragm, and a packing-ring fitting upon said ring and projecting from the outer surface of said diaphragm, substantially as described.

25 4. In a train-pipe coupling, a coupling member having a perforated pipe-head, an annular recess at the outer face of said pipe-head, an annular diaphragm f^3 , a retaining-ring f^4 , and a forwardly-projecting packing-ring of 30 relatively hard material carried by said diaphragm near its inner margin, substantially as and for the purpose set forth.

5. In a train-pipe coupling, a coupling member having a perforated pipe-head, an annular recess at the outer face of said pipe-head, 35 an annular diaphragm f^3 , a retaining-ring f^4 , rings f^5 , f^7 forming a binding for the inner margin of said diaphragm, and a packing-ring f^8 secured to the ring f^5 , substantially 40 as described.

6. In a train-pipe coupling, the combination 45 of an integrally-formed coupling member provided with pipe-heads b , c and d , diagonally opposite horns b' , b^2 having at their bases shoulders p^2 separated by convex surfaces p , and having, also, at their bases inner concave surfaces p' , one junction between each horn-base and convex surface p lying in substantially the same vertical plane and suitable 50 gaskets for said pipe-heads, substantially as described.

7. In a train-pipe coupling, the combination 55 of a coupling member, a central pipe-head b provided with an air-actuated gasket e , a pipe-

head c vertically above and supported from a head b and provided with an air-actuated gasket e , a pipe-head d vertically below the head b and provided with a diaphragm-actuated packing-ring f^8 , and diagonally opposite guide-arms b' , b^2 provided with interlocking 60 surfaces for engaging a duplicate coupling member and preventing relative movement between the coupling members, except in the direction of longitudinal separation, substantially as and for the purpose set forth. 65

8. In a train-pipe coupling, the combination 70 of a coupling-head, a metallic train-pipe joined thereto and formed with a loop imparting elasticity to the train-pipe and permitting longitudinal movement of said head, and a spring interposed at said loop and reinforcing the resilience of the pipe, substantially as and for the purpose set forth.

9. In a train-pipe coupling, the combination 75 of a coupling-head, a train-pipe connected therewith and formed with a loop imparting elasticity to the pipe and permitting longitudinal movement of said head, spring-retainers connected with said pipe at the neck of said loop, and a spring interposed between said 80 retainers, substantially as and for the purpose set forth.

10. In a train-pipe coupling, a movable coupling-head having steam and air passages whose orifices are in the same vertical plane, 85 a soft yielding air-expanded gasket at the air-passage orifice having a transverse outer bearing-surface, a steam-actuated diaphragm at the steam-passage orifice equipped with a comparatively hard packing-ring having a 90 transverse outer bearing-surface, said gaskets being adapted to form a tight joint with corresponding gaskets of a companion coupling-head under longitudinal pressure between coupling-heads, substantially as described. 95

11. In a train-pipe coupling, a coupling-head having annular recesses, an annular diaphragm secured at the shoulder of one of said recesses, and a packing-ring secured to 100 the outer face of said diaphragm near the inner margin thereof, substantially as described.
